GAME PIECE BOX

William W. Knox, Concord, Ohio, assignor to Mag-Nif, Inc., Mentor, Ohio

Filed May 13, 1971, Ser. No. 143,295

Term of patent 14 years

Int. Cl. D21—01

U.S. Cl. D34—5

FIG. 1

FIG. 1 is a top plan view of a game piece box showing my new design;

FIG. 2 is an elevational view thereof; and

FIG. 3 is a perspective view thereof with some of the pivotal tabs selectively pivoted to substantially horizontal positions.

I claim:

The ornamental design for a game piece box, as shown and described.
